(57) **CLAIM**

The ornamental design for a computer platform with forearm support, as shown.

DESCRIPTION

FIG. 1 is a front perspective view from the top of the computer platform with forearm support showing my new design;

FIG. 2 is a rear perspective view from the bottom thereof;

FIG. 3 is a front view thereof;

FIG. 4 is a top plan view thereof;

FIG. 5 is a rear view thereof;

FIG. 6 is a left side view thereof;

FIG. 7 is a bottom plan view thereof; and,

FIG. 8 is a right side view thereof.
